UNITED STATES PATENT OFFICE

HOWARD M. LEONARD, OF SOUTH BEND, INDIANA, ASSIGNOR, BY MESNE ASSIGNMENTS, TO BENDIX AVIATION CORPORATION, A CORPORATION OF DELAWARE

ENGINE

Application filed March 7, 1927. Serial No. 173,246.

This invention relates to engines, and is illustrated as embodied in a two-cycle engine of the Diesel type. An object of the invention is to provide simple means for securing the high pressures necessary in an engine of this type, and improved means for injecting the fuel, preferably by arranging a fuel-feeding plunger for movement in the cylinder head along an axis parallel to the axis 10 of the engine cylinder. I also prefer to form a recess in the head of the engine piston, into which projects that part of the cylinder head which carries the fuel-feeding means, so that the fuel may be injected laterally into 15 the annular space so formed.

The above and other objects and features of the invention, including various novel and desirable details of construction, will be apparent from the following description of the 20 illustrative embodiment shown in the accompanying drawing, in which:

The figure is a vertical section through the upper part of the engine, centrally of the engine cylinder.

The illustrated engine is of the two-cycle type, and includes a water-jacketed cylinder 10, and an engine piston 12 operating the usual crankshaft (not shown). A cylinder-head 14 is detachably secured in any desired 30 manner to the end of the engine cylinder 10.

Preferably the center of the cylinder-head 14 is formed with a downwardly-extending cylindrical projection 16, the lower end of which is shown as a detachable plate 18, and which projects into a corresponding recess in piston 12 when the piston is at the upper end of its stroke.

The compression space, aside from that provided by the annular clearance space above 40 piston 12 about the projection 16, and the clearance between the piston and the plate 18, is provided by cutting away piston 12 at 20, opposite a discharge opening or series of openings 20 extending laterally through the 45 side of projection 16 from a plunger cylinder containing a fuel-feeding plunger 22 formed with a passage 24 from its lower end which registers with opening 20 when the plunger is at the lower end of its stroke.

A groove or elongated fuel reservoir 26 is

formed on the lower face of the projection 16, and between that projection and plate 18, the groove being arranged to intersect the lower end of the plunger cylinder. A fuel passage 28, communicating with groove 26, is controlled by a valve 30, which may be operated by the suction of plunger 22 against the resistance of the valve spring 32, or which may be mechanically operated by a suitable cam-shaft if preferred.

Plunger 22 is reciprocated by means operated by a suitable cam or eccentric on a shaft driven by the engine crankshaft, in any usual manner.

In operation, just before the end of the 65 power stroke of piston 12, plunger 22 is raised until it clears the passage 20, and during this movement of the plunger the fuel is fed from passage 28, either by the action of the suction from plunger 22 acting on the valve 30 or by the mechanical operation of the valve. As soon as plunger 22 clears passage 20, the 70 plunger cylinder below the plunger is filled with intensely hot exhaust gases, which vaporize the charge of fuel, already highly heated 75 by contact with plate 18.

Just before piston 12 reaches the upper end of its compression stroke, or just as it reaches that position, plunger 22 is forced downwardly, compressing the mixture of exhaust gases 80 and fuel somewhat more highly than the air at that time compressed in the engine cylinder. As passage 24 registers with passage 20, the mixture of exhaust gases and vaporized fuel rushes into the engine cylinder, at once 85 ignites, and forces piston 12 downwardly on its power stroke.

While one illustrative embodiment has been described in detail, it is not my intention to limit the scope of the invention to that particular embodiment, or otherwise than by the terms of the appended claims.

I claim:

1. An engine comprising a cylinder, a piston therein having a recessed head, a cylinder head having a boss adapted to engage the recess, a plunger cylinder in the boss, a passage from the plunger cylinder to the engine cylinder, a chamber in the boss communicating with the plunger cylinder, a fuel feeding 95

plunger movable in the plunger cylinder, a passage in the plunger cylinder adapted to connect the chamber with the first mentioned passage at the end of the compression stroke of the plunger and means for feeding fuel to the chamber.

2. An engine comprising a cylinder, a piston movable therein having a recess in the head thereof, a cylinder head having a boss adapted to engage the recess, a plunger cylinder in the boss parallel to the axis of the engine cylinder, a passage connecting the plunger cylinder to the engine cylinder, a plate secured to that portion of the boss adapted to engage the recess in the engine piston, a chamber between the boss and plate communicating with the plunger cylinder, a fuel feeding plunger movable in the plunger cylinder, a passage in the plunger connecting the chamber with the first mentioned passage at the end of the compression stroke of the plunger, and means for feeding fuel to the chamber.

In testimony whereof I have hereunto signed my name.

HOWARD M. LEONARD.
